MARCASITE EXPANSION LINK WATCH BAND OR SIMILAR ARTICLE

Irving Kimler, Brooklyn, N. Y.

Application June 20, 1955, Serial No. 36,594

Term of patent 7 years

(Cl. D5—4)

Fig. 1 is a plan view of a marcasite expansion link watch band or similar article showing my new design.

Fig. 2 is an edge view thereof.

Fig. 3 is an enlarged view of one of the links.

The dominant feature of my design resides in the elements disclosed in full lines, said elements being repeated on either side of the narrow link shown as indicated by the broken line.

I claim:

The ornamental design for a marcasite expansion link watch band or similar article, substantially as shown and described.
